J. G. GRAHAM

DRILLING MECHANISM

Filed May 7, 1924

UNITED STATES PATENT OFFICE.

JAMES G. GRAHAM, OF BUTTE, MONTANA, ASSIGNOR TO SULLIVAN MACHINERY COMPANY, A CORPORATION OF MASSACHUSETTS.

DRILLING MECHANISM.

Application filed May 7, 1924. Serial No. 711,530.

My invention relates to drilling mechanisms.

An object of my invention is to provide an improved drilling mechanism. Another 5 object of my invention is to provide an improved drilling mechanism having improved lubricating means therefor whereby oil, as distinguished from grease, may be used. A further object of my invention is to provide 10 an improved automatic lubricating means controlled by the vibration of the drill. A still further object of my invention is to provide an improved lubricating mechanism for the chuck or piston flutes of a drill. Still 15 another object of my invention is to provide such an improved lubricating mechanism which is responsive to vibrations set up in the drilling motor.

In the accompanying drawings I have 20 shown for purposes of illustration three forms which my invention may assume in practice.

In these drawings,—

Fig. 1 is a side elevation, partially in 25 central longitudinal section, of the drilling mechanism in which my improved lubricating mechanism is incorporated.

Fig. 2 is an enlarged detailed sectional view of my improved lubricating mechanism.

30 Fig. 3 is a detailed sectional view, similar to Fig. 2, of the modified form of construction.

Fig. 4 is a side elevation partially in section of the drilling mechanism incorporating 35 my improved lubricating mechanism, showing a modified form of arrangement.

In the illustrative form of my invention shown in Figs. 1 and 2, I have shown the same embodied in a drilling mechanism, generally designated 1, of the drifter type. This mechanism comprises a cylinder 2 having a bore 3 in which a hammer piston is reciprocable having a striking bar 4 adapted to impart a series of blows to the shank of 40 the drill steel 5 carried in a chuck bushing 6.

As shown, this bushing 6 is suitably arranged 45 within an elongated chuck 7 carried in a longitudinally extending bore 8 which is in turn formed within a chuck housing 9 secured as 50 by side rods 10 to the cylinder 2. It will be observed that the striking bar 4 is provided with flutes or grooves 11 cooperating with inwardly projecting lugs 12 formed on a chuck nut 13 suitably threaded as at 14 with 55 in the rear end of the chuck. The hammer

piston, which carries the rifle bar 4, also cooperates with an automatic step by step rotation mechanism, not shown, of the usual ratchet and pawl type which is adapted to impart intermittent rotary movement to the 60 striking bar and consequently to the chuck 7 and chuck bushing 6, which carries the drill steel 5. The chuck housing 9 is also provided with a radially extending port 15 which is closed by a removable filler plug 16 65 and this port communicates with an annular groove 17 formed by an enlarged portion of the rear end of the bore 8. The forward end of the cylinder 2 is provided with a forwardly projecting portion 18 having an 70 annular portion 19 which fits into the rear end of the bore 8 and with which the rear end of the chuck 7 engages. This portion 18 is herein provided with an annular groove 20 which cooperates with the groove 17 in 75 the chuck housing, forming a chamber 21 adapted to receive lubricant, herein oil. It will also be noted that the annular portion 19 is provided with a plurality of longitudinally extending bores 22 into which my improved 80 lubricating mechanism, generally designated 23, is disposed.

This improved mechanism comprises a plug 24 pressed within one of the bores 22 against a shoulder 25 and is provided with 85 an axially disposed bore 26 into which a pin member 27 is inserted of slightly smaller diameter than the bore 26 and which is provided with a head 28 and an angular or bent-over portion 29 on the opposite end from the 90 head 28, thereby preventing displacement of the pin member 27. The head 28 forms a valve member which cooperates with the end of the bore 26 to control the flow of lubricant from the chamber 21 to an annular groove 95 30 formed in the annular portion 19 which in turn communicates with the flutes or grooves 11 formed in the striking bar 4 and with the bore 8 in which the chuck 7 rotates, lubricating the same.

In the form of my invention shown in Fig. 3, it will be noted that I have provided a plug member 31 inserted in the bore 22 and this plug member is provided with an annular bore 32 which communicates with the groove 30 by means of the plurality of ports 33 formed in the forward end thereof. The rear end of the bore 22 communicates with the chamber 21 by way of the port 34 which is normally closed by a conical end 100 110

seated valve 35 held in position by means of the light coil spring 36 disposed within the chamber 32.

In the form of my invention shown in Fig. 4, I have shown my improved lubricating mechanism embodied in a drilling mechanism, generally designated 37, of the "stopper" which comprises a drilling motor cylinder 38 having a bore 39 in which a hammer piston 40 is reciprocable having a forwardly projecting striking bar 40 adapted to impart a series of blows through a striking block 41 to a drill steel 42. The drill steel 42 is carried in a chuck 43 suitably threaded within the forward end of the chuck sleeve 44 which is arranged in a bore 45 formed within a chuck housing 46 suitably secured to the cylinder 38 as by side rods 47 in a well known manner. The striking bar 40 of the piston 40 is provided with flutes or grooves 48 which cooperate with inwardly projecting lugs 49 formed on a chuck nut 50 suitably threaded as at 51 within the rear end of the chuck sleeve 44. Arranged longitudinally of the chuck housing 46 is a bore 52 which forms a lubricant chamber having its forward end closed by a removable filler plug 53 and which communicates at its rear end through my improved lubricating mechanism, generally designated 23, with radially extending grooves 54 formed in the chuck sleeve and nut leading to the grooves 48 formed in the striking bar and with the annular bore 45 in which the chuck rotates.

The mode of operation of my improved lubricating mechanism is as follows. During the drilling operation the hammer piston 40 imparts a series of blows to the drill steel 42 and rotates the latter, causing the piston 40 to set up a series of vibrations within the drilling mechanism. These vibrations are imparted to the lubricator 23 causing the valve forming head 28, by means of inertia, to intermittently open and close communication between the bore leading to the chamber 21 and the groove 30 which in turn communicates with the grooves 11 in a striking bar 4 and with the bore 8 in which the chuck 7 is rotated, lubricating the same.

The operation of the form of my invention shown in Fig. 3 is substantially similar to that in Figs. 1 and 2. The valve 35 intermittently opens and closes communication, by means of inertia caused by the vibration set up within the drilling motor, between the chamber 21 and the bore 32 formed in the member 31.

In the form of my invention shown in Fig. 4, it will be noted that the vibrations set up by the hammer piston actuating the drill steel cause the automatic inertia operated valve mechanism 23 to permit intermittent communication between the oil chamber 52 and the groove 54 and the bore 45 in which the chuck sleeve 44 rotates, lubricating the

same, the operation of the automatic lubricating mechanism per se being substantially the same as in Fig. 1.

As a result of my improvement, it will be noted that I have provided an improved lubricating mechanism which is automatically operated by inertia caused by the vibrations set up in the drilling motor, thereby insuring a positive supply of lubricant during drilling to the moving parts of the rotation mechanism which is of exceedingly simple and compact construction and which may be manufactured at a minimum of expense and applied to a drill of standard construction with a minimum of change.

While I have in this application specifically described three forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a rock drill, the combination with an impact motor having a cylinder, and a piston reciprocable therein having a forwardly projecting extension, of lubricating means for said extension comprising a lubricant reservoir formed in said cylinder at the forward end thereof, a passage formed in said cylinder and connecting said reservoir with said extension, and means comprising a valve for providing intermittent flow of lubricant through said passage.

2. In a rock drill, the combination with an impact motor having a cylinder, and a piston reciprocable therein having a forwardly projecting extension, of lubricating means for said extension comprising a lubricant reservoir formed in said cylinder at the forward end thereof, a passage formed in said cylinder and connecting said reservoir with said extension, and means comprising a valve operated by the vibrating action of said motor for automatically controlling the flow of lubricant through said passage.

3. In a rock drill, the combination with an impact motor having a cylinder, a hammer piston reciprocable in said cylinder and having a forwardly projecting extension and a chuck housing, of lubricating means for said extension comprising annular grooves formed in the forward end of said cylinder and in said housing cooperating to form a lubricant reservoir, a passage leading from said reservoir to said extension, and means comprising a valve for controlling the flow of lubricant through said passage.

4. In a rock drill, the combination with an impact motor having a cylinder, a piston reciprocable in said cylinder and having a forwardly projecting extension, a chuck

- housing and a rotatable chuck therein, of lubricating means for said extension and chuck comprising a lubricant reservoir formed in the forward end of the motor in said cylinder and housing, a passage connecting said reservoir with said extension and chuck, and means comprising a valve for controlling flow of lubricant through said passage.
5. In a rock drill, the combination with an impact motor having a cylinder, a piston reciprocable in said cylinder and having a forwardly projecting extension, a chuck housing and a rotatable chuck therein, of lubricating means for said extension and chuck comprising a lubricant reservoir formed in the forward end of the motor in said cylinder and housing, a passage connecting said reservoir with said extension and chuck, and means comprising a valve operated by the vibrating action of said motor for automatically controlling flow of lubricant through said passage.
6. In a rock drill, the combination with an impact motor having a cylinder, a piston reciprocable in said cylinder and having a forwardly projecting extension, a chuck housing and a rotatable chuck therein, of lubricating means for said extension and chuck comprising annular grooves formed in the forward end of said cylinder and in said housing cooperating to form a lubricant reservoir, a passage connecting said reservoir with said extension and chuck, and means comprising a valve for controlling flow of lubricant through said passage.
7. In a rock drill, the combination with an impact motor having a cylinder, a piston reciprocable in said cylinder and having a forwardly projecting extension, a chuck housing, a chuck rotatable in said housing, said chuck having its rear end disposed adjacent the forward end of said cylinder, of lubricating means for said extension and chuck comprising annular grooves in the forward end of said cylinder and in said chuck housing cooperating to form a lubricant reservoir, a passage formed in the forward end of said cylinder between the latter and said chuck for connecting said reservoir therewith, and means comprising a valve operated by the vibrating action of said motor for automatically controlling flow of lubricant through said passage.
8. In a rock drill, the combination with an impact motor including a cylinder having a reduced bore at the front end thereof, a rotatable chuck, a hammer piston reciprocable in said cylinder and having a forwardly projecting extension passing through said reduced bore, of lubricating means for said chuck and said bore comprising an annular groove formed in the forward portion of said cylinder surrounding said extension, said groove forming a lubricant reservoir, a passage connecting said reservoir with said reduced bore, and means comprising a valve operated by the vibrating action of said motor for automatically controlling the flow of lubricant through said passage.
9. In a rock drill, the combination with a cylinder, a reciprocable piston having a forwardly projecting extension, and a cylinder head forming portion through which said extension passes, of lubricating means for said extension comprising an external annular groove formed in said cylinder head portion adapted to receive lubricant and having communication with said extension, and means comprising a valve operated by the vibrating action of said motor for automatically controlling flow of lubricant through said extension.
10. In a rock drill, the combination with an impact motor including a cylinder having a reduced bore and a reciprocable piston having a forwardly projecting extension passing through said bore, of lubricating means for said extension comprising a lubricant reservoir formed in the forward portion of said cylinder surrounding said extension, a passage connecting said reservoir with said reduced bore, and means comprising a valve operated by the vibrating action of said motor for automatically controlling the flow of fluid through said passage.
11. In a rock drill, the combination with an impact motor including a cylinder and a rotatable chuck, of lubricating means for said chuck comprising a lubricant reservoir formed in the forward end of said cylinder adjacent the rear end of said chuck and having communication with the latter, and an inertia operated valved means for automatically controlling the flow of lubricant from said reservoir to said chuck.

In testimony whereof I affix my signature.

JAMES G. GRAHAM.

CERTIFICATE OF CORRECTION.

Patent No. 1,679,140.

Granted July 31, 1928, to

JAMES G. GRAHAM.

It is hereby certified that error appears in the printed specification of the above numbered patent requiring correction as follows: Page 2, line 8, before the word "which" insert the word "type"; and that the said Letters Patent should be read with this correction therein that the same may conform to the record of the case in the Patent Office.

Signed and sealed this 25th day of September, A. D. 1928.

(Seal)
